COSMETIC COMPACT AND APPLICATOR

Jacqueline B. Helms, Pacific Palisades, Calif., assignor of one-half to George L. Helms, Pacific Palisades, Calif.

Application August 2, 1946, Serial No. 688,031

4 Claims. (Cl. 132—83)

1

This invention relates to toilet facilities and accessories, and more particularly to such conveniences adapted for use in facial make-up and the freshening and retouching thereof, and has as an object to provide an improved such facility especially suited to maintain conveniently available and to promote the effective application of facial rouge.

A further object of the invention is to provide an improved rouge container and associated applicator arranged for coaction as a compact, fully closed, conveniently transportable unit separable at will for cooperative employment of its constituent elements.

A further object of the invention is to provide a unitary assembly of all elements and facilities essential to the application of facial rouge in form immediately available for use.

A further object of the invention is to provide an improved rouge container and applicator combination arranged for reconditioning through successive replacements of depleted and deteriorated elements.

A further object of the invention is to provide an improved construction and combination of elements comprising a cosmetic compact and applicator unit that is simple and inexpensive of manufacture, convenient of use, practical in concept, pleasing in form, susceptible of development in a variety of colors and finishes from various commonly-available materials, and employable to enhance the felicitous effect of rouge adornment.

With the foregoing and other objects in view, my invention consists in the construction, arrangement, and combination of elements as hereinafter set forth, pointed out in my claims, and illustrated by the accompanying drawing, in which—

Figure 1 is a front or face elevation of a simple, preferred embodiment of the invention. Figure 2 is a side elevation of the showing according to Figure 1. Figure 3 is a cross section, on an enlarged scale, taken substantially on the indicated line 3—3 of Figure 1. Figure 4 is a side elevation of a slightly modified embodiment of the invention with the major elements of the assembly separated and opened into position for practical use.

In the construction of the improvement as shown, an applicator, employable to transfer rouge from a suitable supply to the face of the user and to spread and blend the transferred cosmetic in the place and position of its use, is illustrated as comprising a holding and manipulating member consisting of a disc 10, an in-

tegrally-related, radially-disposed handle 11, and a pad 12 seated in and to project beyond one face of the disc 10. The disc 10 and integral handle 11 may be formed from any suitable material, such as wood, metal, synthetic resins, and the like, in any convenient or appropriate manner, in such size, relative proportions, and finish as may be deemed desirable, one face, the back, of the said disc being non-intersected, solidly contoured to pleasing form, and perhaps ornamented, while the other face, the front, of said disc is formed with a concentric, annular flange or rib 13 outstanding axially from the disc face with its outer margin stepped inwardly from the disc periphery and defining a relatively large, shallow, cylindrical recess intersecting the disc front face in axially-perpendicular relation with the handle 11. The applicator pad 12 is circular in outline and of a diametric size receivable within the recess defined by the flange 13, said pad being preferably secured to and carried by a circular, relatively stiff, backing member 14 frictionally engageable within and against the base of the disc recess to retain the pad against accidental separation from its disc mounting, and said pad, in a thickness considerably in excess of the recess depth, is of any suitable or conventional construction productive of moderate pad compressibility and of a soft, fluffy, exterior surface texture such as or analogous to lamb's wool. The pad 12, with its backing member 14, is removable and replaceable relative to the disc 10, thereby providing for rehabilitation of the applicator when one pad surface has become worn, caked, or for any reason unsuited for further use, and the pad assembly thickness is such as to project the pad crown well beyond the plane of the flange 13 outer margin when the backing member is seated against the disc recess base, so that the complete applicator unit may be manipulated by means of its handle 11 to transfer rouge from the surface of a rouge cake or wafer to the pad crown and thence to the face of a user where it may be spread, blended, and toned by means of the pad to a pleasing, professionally-artistic effect.

To complement the utility of the applicator unit above described, a rouge-containing, mirror-equipped compact is arranged for separable coaction with said unit in protective covering relation with the pad 12, said compact taking the form of an axially relatively short, cylindrical housing 15 having a maximum diameter equalling that of the disc 10. The housing 15 may correspond in material, color, and finish with the

disc 10 and handle 11, or may contrast therewith in any such respect, as taste and aesthetic considerations may dictate, but whatever may be its specific similarities or distinctions, said housing is axially recessed at one end to provide an annular flange 16 sized to telescopically receive and close about and over the disc flange 13 and has the base of its axial recess concaved into clearing accommodation with the pad 12 crown when the housing flange 16 is engaged with and closed about the disc flange 13 in the manner shown in Figure 3, in which relation the contacting flange surfaces frictionally engage with a slight taper effective to hold the housing 15 to and against separation from the disc 10 while permitting intentional, manual separation of said elements.

The end of the housing opposite to the flange 16 is likewise axially recessed to a depth sufficient to accommodate and house a conventional rouge cake 17 carried by a backing member 18 seatable and frictionally or adhesively retainable against the recess base to present the cake 17 face to and for exposure through the recess open end, the said cake being thus wholly housed within and associated for removal and replacement relative to its recess, and a circular closure member or cover 19 is sized to marginal registration with the housing 15 and is hinged, as at 20, to said housing for selective actuation between opening and closing cooperation with the rouge-cake-accommodating housing recess, a spring clip 21 on the margin of the cover 19 diametrically opposite the hinge 20 and engageable with a retaining lug or rib on the housing 15 exterior margin being provided to latch and releasably hold the cover 19 in closed relation with the housing recess and its contents. The inner face of the cover 19 is worked to receive, seat, and permanently mount a mirror 22 in clearing relation with the rouge cake surface when said cover is closed and in position for convenient use when said cover is open, thus perfecting the utility of the assembly.

The modified construction typified by Figure 4 is essentially and operatively the same as that hereinabove described and differs from that of the other views only in that external threads 23 are provided on the outer surface of the flange 13 for cooperation with complementary internal threads on the flange 16 inner surface to constitute an alternative and somewhat more positive means for separably interengaging the applicator and compact units of the assembly.

With the cover 19 closed and latched over the rouge cake and the housing 15 engaged with the disc 10 in the manner shown in Figure 2, the improved device has the form of a unitary assembly conveniently transportable in a purse, bag, or pocket and free from damage-productive corners, angles, or edges; the applicator and rouge cake surfaces being wholly covered and protected within the closed assembly to obviate any smearing, discoloring, or soiling contact thereagainst. In the practical use of the device, the housing 15 is manually separated from the disc 10 to uncover the crown of the applicator pad 12, the cover 19 is unlatched and opened to expose the face of the rouge cake 17, and the applicator is then manipulated by one hand of the user to pick up a coating of rouge from said cake and to apply the same to the user's face, the housing 15 with its cover 19 open being conveniently held in the user's other hand with the rouge cake surface readily available and the mirror 22 in position for visual reference to check and control applicator manip-

ulation effect. After the transferred rouge has been spread and blended by the applicator to attainment of the desired result, the cover 19 is closed and latched over the rouge cake and the housing 15 closed over the pad 12 in engagement with the disc 10 to reestablish the unit assembly in form and condition for storage and ready availability against a future occasion of use.

Since many changes, variations, and modifications in the specific form, construction, and arrangement of the elements shown and described may be had without departing from the spirit of my invention, I wish to be understood as being limited solely by the scope of the appended claims, rather than by any details of the illustrative showing and foregoing description.

I claim as my invention:

1. A cosmetic compact and applicator comprising, a disc formed with an integral, coplanar, radially-extending handle and an integral, annular flange concentrically upon and outstanding perpendicularly from one of its faces to define a shallow recess thereon, an applicator pad removably and replaceably engaged in said recess for projection of its working surface beyond the plane of the flange margin, a cylindrical housing axially recessed at one end to coat with said flange and thereby separably mount said housing on said disc in covering relation with said pad, a shallow, coaxial recess in the other end of said housing, cosmetic material removably and replaceably accommodated in said latter recess, a cover hinged to said housing to close over said latter recess and the cosmetic material therein, means for latching said cover in closing relation with the recessed end of the housing, and a mirror fixed to the inner face of said cover.

2. A cosmetic compact and applicator comprising, a disc formed with an integral, coplanar, radially-extending handle and an integral, annular flange concentrically upon and outstanding perpendicularly from one of its faces to define a shallow recess thereon, an applicator pad removably and replaceably engaged in said recess for projection of its working surface beyond the plane of the flange margin, a cylindrical housing formed with coaxial, non-communicating recesses opening oppositely through its ends, an annular wall about one of said recesses sized to coat with said flange and thereby separably mount the housing on said disc in covering relation with said pad, cosmetic material removably and replaceably accommodated in the other housing recess, a cover hinged to said housing to close over said latter recess and the cosmetic material therein, means for latching said cover in closed relation over its associated housing end, and a mirror constituting the inner face of said cover.

3. A cosmetic compact and applicator comprising, a disc formed with an integral, coplanar, radially-extending handle, an applicator pad removably and replaceably associated with and projecting beyond one face of said disc, an annular flange integrally outstanding from said disc peripherally about said pad an axial distance less than the pad extension beyond the disc face, a cylindrical housing formed with an end recess telescopically engageable over said flange in covering relation with said pad, coating means on said housing and flange interengageable to separably connect said housing to said disc, a recess opening through the other end of said housing for the accommodation of cosmetic material, a cover hinged to said housing in closing cooperation with said latter recess, means for latching

said cover to and in closing relation with the associated housing end, and a mirror constituting the inner face of said cover.

4. In a cosmetic compact and applicator having a disc formed with a radially-extending handle and an applicator pad removably and replaceably associated with and to project beyond one face of said disc, a transversely-partitioned housing separably engageable at one end with said disc in covering relation with said pad, cosmetic material removably and replaceably accommodated in the end of said housing remote from said disc, a cover hinged to the cosmetic-accommodating housing end, and a mirror constituting the inner face of said cover.
